UNITED STATES PATENT OFFICE.

HENRY G. YATES, OF SAN FRANCISCO, CALIFORNIA, ASSIGNOR, BY DIRECT AND MESNE ASSIGNMENTS, TO THE PLANETARY WHEEL MANUFACTURING COMPANY, OF CALIFORNIA.

CAR-WHEEL.

SPECIFICATION forming part of Letters Patent No. 278,843, dated June 5, 1883.

Application filed October 2, 1882. (No model.)

To all whom it may concern:

Be it known that I, HENRY GILES YATES, a citizen of the United States, residing at San Francisco, in the county of San Francisco and 5 State of California, have invented a new and useful Car-Wheel, of which the following is a specification.

My invention relates to improvements in car-wheels in which the wheel revolves around a 10 fixed axle in conjunction with anti-friction bearing or guiding rollers placed within the body of the wheel, or, in other words, so as to produce a sun-and-planet motion; and the objects of my improvements are to provide a 15 means whereby the friction of the parts is reduced to a minimum, and the heating of the boxes and axles prevented, and little or no lubrication required. I attain these objects by the mechanism illustrated in the accompanying 20 drawings, in which—

Figure 1 is a sectional plan of my car-wheel with one disk-plate removed. Fig. 2 is a vertical sectional elevation of the wheel. Fig. 3 is a plan view of one-half of the wheel-rim with one disk removed.

Similar letters refer to similar parts throughout the several views.

The body, tire, and flange A of my wheel are either cast whole or in two separate parts in 30 central vertical sections, with the flange upon one-half of the rim, or the sections may be forged separately from good wrought-iron, and when so constructed separately the two parts are secured by square-shanked bolts, which 35 may be of any convenient number.

To procure lightness, the webbing of the wheel may have a number of holes of any form made through the parts, while suitable central openings, B B, are formed in the web to receive the disk-plates, which form the hub or nave, to be hereinafter more fully described.

The hub is constructed in two parts, each the counterpart of the other, and formed of two disks or plates, D D', with inwardly-extending bosses with rounded bases, and flanges E at the outer edges of the disks, and when in position the inner face of one of these bosses is opposed to and rests against the face of the other or opposite one in close proximity, and 50 a groove, F, is formed around the hub, in which

the inner edges of the friction or bearing rollers operate.

The frictional bearing rollers or wheels G are constructed of flat pieces of metal, and are provided with rounded edges. They are placed 55 in suitable numbers within and so as to occupy the hollow space of the web of the wheel, and have sufficient room for play, but are not arranged so closely as to bind one against the other.

In practice, when the wheel is cast or forged in sections, the parts are first bolted together, and the bearing wheels or rollers passed through the center or openings in the web and arranged in the manner shown in Fig. 1, when 60 the two disk-plates which form the hub are placed in position in the openings at each side of the wheel, and the end of the axle H is forced into and through the openings in the center of the hub-plates by hydraulic or other 65 power until the end of the axle is projected a sufficient distance beyond the face of the wheel in order to connect the trucks of the car or the car-axle box to the end of the axle, and this 70 connection may be made in the usual way and 75 with the ordinary boxing and hangers; but no lubricant will be required for the axle-box, as the axle does not revolve. If it should be deemed necessary, however, to key the hub to the axle, the axle may be forced through the 80 inner hub of the inner disk-plate and keyed, when the other disk may be operated upon in like manner and keyed to the axle.

When the parts are in position it will be observed that the wheel is held loosely, or so as 85 to have a little play between the two disk-plates laterally, and that the periphery of the disk-plates fits loosely into the circular openings in the web, so that sufficient room is had for the free action of the axle and hub without binding of the parts, while the flanges upon the outer edges of the disk-plate overlap the webs and limit the lateral play of the wheel, and, furthermore, that the supporting or friction 90 wheels operate in the grooved hub between the disk-plates and the web of the wheel in a reverse manner to the trend of the wheel, with their upper bearings upon the inner face of the rim of the wheel and their lower bearing in the groove around the hub, in which position 95 100

they are held between the disk-plates and the web of the wheel, and lateral or vertical movement or binding is prevented.

Having thus described my invention, what I claim, and desire to secure by Letters Patent, is—

The combination, with the fixed axle H, of a car-wheel composed of the flanged and recessed tire A, the flanged hub-disks D D', constructed as described, and forming with the

tire an annular recess, F, and the rollers G G, arranged in said recess, all substantially as set forth.

In testimony that I claim the foregoing I have hereunto set my hand and seal this 19th day 15 of September, 1882.

HENRY G. YATES. [L. S.]
